UNITED STATES PATENT OFFICE.

JOHN C. STURGEON, OF ERIE, PENNSYLVANIA.

OVERHEAD TROLLEY.

No. 921,025.

Specification of Letters Patent.

Patented May 11, 1909.

Application filed January 29, 1908. Serial No. 413,193.

To all whom it may concern:

Be it known that I, JOHN C. STURGEON, a citizen of the United States, residing at Erie, in the county of Erie and State of Pennsylvania, have invented certain new and useful Improvements in Overhead Trolleys; and I do hereby declare the following to be a full, clear, and exact description of the invention, such as will enable others skilled in the art to 10 which it appertains to make and use the same, reference being had to the accompanying drawings, and to the letters of reference marked thereon, forming part of this specification.

15 My invention relates to overhead trolleys, and has for its objects: First. The construction of a trolley-wheel and harp therefor in such a manner that the minimum of weight consistent with adequate strength is secured 20 therein. Second. The combination with the trolley-wheel hub of a removable graphite lubricated sleeve, and a hollow, perforated, non-rotatable shaft-bearing, upon which said 25 sleeve rotates, having removable screw-plugs in the ends thereof the heads of which operate against the arms of the harp to firmly secure the hollow shaft-bearing therein.

These and other features of my invention are hereinafter fully set forth and described, 30 and illustrated in the accompanying drawings, in which:

Figure 1 is a side view in elevation of an overhead trolley embodying my invention. Fig. 2 is a vertical section of the same on the 35 line *x*, in Fig. 1. Fig. 3 is a longitudinal section of the removable graphite lubricated wheel-hub sleeve of my invention. Fig. 4 is a longitudinal section of the non-rotatable hollow shaft-bearing of my invention. Fig. 40 Fig. 5 is a sectional detail of the upper portion of one of the harp arms. Fig. 6 is a view in elevation of the inside of the same. Fig. 7 is a cross section of the same on the line *y*—*y* in Figs. 5 and 6.

45 In these drawings A is a trolley-harp, having arms A' and A² with their upper ends A³ and A⁴ turned inward toward the sides of the trolley-wheel to be mounted therein, far enough to prevent the trolley-wire from passing down between the said upper ends of the harp arms and the wheel. This trolley-harp, I preferably construct of steel or other suitable metal plate, formed into shape in suitable dies. I can, however, make the harp of 50 cast metal, but as this materially increases its weight I do not deem it so desirable. The

arm A² is preferably provided with shoulders a⁵ a⁶ against which the washer J' (hereinafter referred to) contacts, and between these shoulders there is a recess into which 60 the end of the contact spring G (hereinafter referred to) extends and contacts with the outside of said washer J' between the shoulders a⁵ a⁶ as clearly illustrated by dotted lines in Figs. 6 and 7.

65 B is an ordinary rod secured in the shank of the trolley harp A, of suitable length to be inserted in a trolley pole so as to connect the harp A therewith.

The trolley-wheel forming part of my invention, I make of duplicate disks D pressed out of thin sheet metal, each of said disks D being so shaped in suitable dies as to form an outwardly projecting central sleeve d, and a peripheral flange d' thereon, and in 70 the bottom of the groove formed between these peripheral flanges d' d', when the disks D D are placed together, I place a contact-ring C made preferably of copper, secured in place therein by means of rivets c, or by 75 other suitable means, which operate to secure the disks D D and the contact-ring C firmly together. The hub E of this wheel is preferably made of a section of ordinary brass tubing cut to the proper length and is 80 secured in place by being firmly pressed into the outwardly projecting central sleeves d d of the disks D D. In this hub E, I secure a removable sleeve-bearing F, preferably made of a section of phosphor-bronze, or other 85 suitable tubing, in which staggered holes f are made, and which holes are filled with a suitable graphite composition f'. These 90 holes f being preferably so located in the sleeve F that the end rows f² of one set of 95 said holes f, are cut at one end of the sleeve F, and the rows f³ of the opposite set of holes are cut at the opposite end of the sleeve, as is clearly shown in Figs. 2 and 3, so that the 100 end holes so located, operate to lubricate the ends of the sleeve.

The shaft-bearing H, upon which the sleeve F rotates, is non-rotatable, and is made tubular in form, and as shown has an internal thread h cut in each end thereof, 105 and holes h' are bored through it, as shown in Fig. 4, to permit a lubricant within the tube, to pass out therefrom under the sleeve F to lubricate it.

For securing this shaft-bearing H in place 110 between the arms A' and A² of the trolley-harp A, I provide screw-plugs I I' adapted

to be screwed into the threaded portions *h h* in the ends of the shaft-bearing *H*; these plugs *I I'* are provided with squared heads *i i'* adapted to engage the outsides of the 5 trolley-harp arms *A' A²*, the harp-arm *A'* being provided with an opening *a* large enough to allow the shaft-bearing *H* to pass through it, and the harp-arm *A²* with an opening only large enough to permit the 10 screw-plug *I'* to pass through it, so that when the shaft-bearing *H* is in place one end thereof is closed by the screw-plug *I*, which abuts against the end thereof and against the outer face of the harp-arm *A'*, which is 15 provided with a lug *a²* which engages the head *i* of the plug *I* and prevents its unscrewing. In lieu, however, of making the shaft-bearing *H* with the screw-plug *I* closing one end thereof, it can be bored out of 20 solid metal, and the head *i* formed thereon integral therewith if desired, and for the purpose of conveniently filling the tubular chamber *H'* in the shaft-bearing *H*, I preferably make an opening through the closure 25 *I* and head *i* thereof, which I close by a small removable screw *i²*, whereby the chamber *H'* can be readily filled with suitable lubricant. The opposite end of the shaft-bearing *H*, at 30 the same time engages the inside face of the harp-arm *A²*, and the screw-plug *I'* is then secured in place, closing the central opening in the shaft-bearing *H*, and firmly clamping the end thereof against the inner face of the harp-arm *A²*.

35 On the shaft-bearing *H* between the ends of the wheel-hub *E* and of the removable sleeve *F* therein, and the inner faces of the harp arms *A' A²*, I place contact washers *J J'* which contact with both the ends of the 40 hub *E* and sleeve *F*. The outside of the washer *J* contacting with the inner face of the harp-arm *A'*, and the outside of the washer *J'* contacting with the shoulders *a³ a³* on the inner face of the harp-arm *A²*, and to 45 the inside of the harp arm *A²*, I secure a spring contact arm *G*, which extends upward into the recess between the shoulders *a³ a³* on the said harp-arm and has an opening *g* therein embracing the shaft-bearing *H* and engaging the outer face of the contact 50 washer *J'* with a spring pressure, so that at all times, the washers *J'* and *J*, the wheel-hub *E*, the bushing *F* and the inner faces of the harp-arms *A' A²*, are maintained in 55 close contact.

In view of the foregoing description of my invention, it is believed that its construction and operation will be clearly understood, without further description thereof.

60 Therefore having described my invention so as to enable others to construct and use the same, what I claim as new and desire to secure by Letters-Patent of the United States is:

65 1. The combination in an over-head

trolley wheel, of two sheet metal disks, an outwardly projecting hub collar and an outwardly inclined peripheral flange on each of said disks, a peripherally concaved contact ring secured between said flanges and supported thereon, rivets through said disks under said flanges, a tube pressed into the hub collars on said disks so as to form a continuous wheel-hub securing the centers of the disks together, and a bushing removably inserted in said hub, substantially as set forth. 70 75

2. The combination in an overhead trolley-wheel, of two metal disks, central collars thereon, inclined flanges on the peripheries 80 of said disks, a contact-ring secured between the bases of said flanges, a tubular hub secured in said central collars, a removable graphite lubricated bushing in said tubular hub, and a non-rotatable hollow perforated 85 shaft-bearing upon which said bushing rotates, substantially as set forth.

3. The combination in an overhead trolley, of a trolley harp, and a trolley-wheel consisting substantially of two sheet metal disks 90 having outwardly projecting central collars and peripheral flanges thereon, a contact ring secured between said flanges, a tubular hub secured in the central collars on said disks, and a removable bushing in the tubular hub, with a non-rotatable hollow perforated shaft-bearing on which said bushing rotates, and means for closing the ends thereof 95 adapted to secure said shaft-bearing between the trolley-harp arms, substantially as 100 set forth.

4. The combination of a trolley-harp, a trolley-wheel consisting substantially of two metal disks, central collars thereon, inclined flanges on the peripheries of said disks, a peripherally concaved copper contact-ring secured between said flanges, a tubular hub pressed into the central collars on said disks, and a bushing removably inserted in said hub, a hollow perforated shaft bearing secured between the arms of the trolley harp, loose washers thereon contacting with the ends of the wheel-hub and with the inner faces of the trolley-harp arms, and a contact-spring secured to one of the arms of the trolley-harp and extending along a recess 110 therein so as to contact with the outside of one of said washers, substantially as set forth. 115

5. The combination in an overhead trolley, 120 of a trolley-harp, and a trolley-wheel consisting substantially of two metal disks having outwardly projecting central collars, and outwardly inclined peripheral flanges thereon, a contact ring riveted between the bases 125 of said flanges, a tubular hub secured in the central collars on said disks, and a removable bushing in the tubular hub, with a non-rotatable hollow perforated shaft-bearing on which said bushing rotates, contact collars 130

on said shaft-bearing at the ends of the wheel-hub and bushing therein, a contact spring secured to one of the arms of the trolley-harp and engaging the contact washer 5 at one end of the wheel-hub, and means for closing the ends of the shaft-bearing adapted to secure it in place between the trolley-harp arms, substantially as set forth.

6. The combination in a trolley harp of 10 one arm having a hole therethrough to receive a shaft-bearing, and another arm provided with inwardly projecting shoulders to engage the end of a wheel-hub on the inner face thereof having a recess there-between

and having an opening in said recess through 15 said arm to receive a screw for supporting one end of the shaft-bearing, and a contact spring secured to the inside of said arm and extending into the recess between the shoulders on the inner face of said arm, substantially as set forth. 20

In testimony whereof I affix my signature, in presence of two witnesses.

JOHN C. STURGEON.
